REFRIGERATOR DEFROSTING METHOD
AND APPARATUSFred B. Fink, Des Moines, Iowa, assignor to
Kelvinator Corporation, Detroit, Mich., a cor-
poration of Michigan

Application April 18, 1932, Serial No. 605,973

31 Claims. (Cl. 62—4)

An object of my invention is to provide a method of defrosting a cooling unit and an apparatus of simple, durable and inexpensive construction for performing the method.

5 A further object is to provide a method of defrosting a cooling unit comprising the circulation of heated fluid through a conduit which is in heat conducting relation to the cooling unit, the fluid being normally cool, but heated for 10 the defrosting operation by an electric heater or the like, an automatic electric switch being provided to control such heating in accordance with an undesirable low or a lower than normal temperature condition of the cooling unit as 15 caused by the accumulation of frost thereon.

A further object is to provide an apparatus for defrosting a cooling unit comprising a fluid conduit which is in heat conducting relation to the cooling unit and means for heating a fluid 20 and circulating it through the conduit whereby defrosting may be accomplished in a minimum of time with a minimum rise of temperature in the space surrounding the cooling unit.

More particularly, it is my object to provide 25 a defrosting apparatus for the cooling unit of a refrigerator which consists of a fluid conduit in metallic contact with the cooling unit of a refrigerator and a tank connected therewith, the conduit and the tank forming a closed fluid circuit for a defrosting fluid.

A further object is to provide heating means 30 for the fluid which can be operated to heat the fluid and to circulate it through the conduit when defrosting is desired.

35 Still a further object is to provide a defrosting apparatus for a mechanical refrigerator or one in which mechanical means is provided to produce refrigeration and operated by an electric motor and to also provide automatic means for 40 causing the defrosting operation and simultaneously therewith preventing any refrigerating operation of the refrigeration mechanism.

A further object is to control the defrosting 45 operation in exact accordance with the temperature condition of a fin or other element of a cooling unit so that defrosting is accomplished when and only when a predetermined thickness of frost has formed on the cooling unit, the automatic means being operable to discontinue 50 the defrosting operation immediately upon the frost on the cooling unit being substantially melted. The thickness of frost indirectly regulates the temperature of the cooling unit by 55 acting as an insulator and thus causing (as it builds up) the refrigerating machine to operate

longer each running cycle thereof to thereby cause a gradual decrease in the temperature of the cooling coil to below normal.

With these and other objects in view my invention consists in the construction, arrangement 5 and combination of the various parts of my method and apparatus, whereby the objects contemplated are attained, as hereinafter more fully set forth, pointed out in my claims, and illustrated in the accompanying drawing, in which:

Figure 1 is a side elevation of a refrigeration 10 cooling unit and my defrosting apparatus connected therewith, part of the figure being diagrammatic.

Figure 2 is a plan view of the cooling unit 15 and defrosting mechanism, a control switch shown in Figure 1 being omitted.

Figure 3 is a vertical enlarged sectional view 20 on the line 3—3 of Figure 1 showing a heating means for defrosting fluid.

Figure 4 is a sectional view on the line 4—4 25 of Figure 1 showing the relationship between the defrosting fluid conduit and fins of the cooling unit.

Figure 5 is a sectional view showing my invention applied to a jacket type of cooling unit; 30 and

Figure 6 is a sectional view showing it applied to a plate coil type of unit.

On the accompanying drawing, I have used 35 the reference character A to indicate generally the cooling unit of a refrigeration mechanism. The cooling unit A, as illustrated in Figures 1 and 2, comprises a refrigerant conduit 16 and heat absorbing fins 12. A unit of this character 40 is usually mounted in proper position within an insulated room or display case to cool the air therein for thus providing a compartment in which foods especially can be kept from spoiling.

A cooling unit which is cooled by means of 45 mechanical refrigeration accumulates frost and the accumulation is more or less rapid, depending on the moisture condition of the air surrounding the unit. Repeated attempts have been 50 made to provide some form of automatic defrosting mechanism for cooling units of refrigerators and at present many of them are defrosted by hand which is accomplished by pouring water over the unit and letting it drain off. This method is both unsatisfactory and inefficient 55 and since it is a hand operation, involves the time of an operator as well as the attendance of someone to observe the condition of the cooling unit so that it can be defrosted whenever necessary.

- Another way of defrosting a cooling unit is to shut off the refrigeration mechanism and let the compartment in which the cooling unit is mounted gradually rise in temperature whereupon the frost will eventually melt from the unit. This raises the temperature of the food containing compartment however and if the foods, especially meats, are not removed to some other refrigerator, spoilage may occur.
- 10 I have provided a defrosting unit indicated generally by the reference character B which is both automatic and efficient. To make it automatic I provide a control such as the one indicated by the reference character C.
- 15 My defrosting unit B includes a conduit 14 and a tank 16. The conduit 14 extends from an outlet 14a in the top of the tank 16 to an inlet 14b in the bottom of the tank. The parts are all hard-soldered, brazed, welded or assembled together by suitable pipe fittings or joints in any well known manner so as to form a closed fluid system. I provide a stand pipe 18 extending upwardly from the outlet 14a for the purpose of providing an air cushion as indicated at 20 in 25 Figure 3.
- A suitable cap 22 may be screwed on the top of the stand pipe 18 to seal the system after the proper amount of fluid 24 is placed therein to leave the desired space for the air cushion 20.
- 30 Instead of the cap 22, the upper end of the pipe 18 may be permanently sealed by welding or the like if this is found desirable.
- The conduit 14 is in intimate contact with the fins 12 so as to provide a ready path for conducting heat from the fluid 24 and the conduit 14 to the fins 12 and the refrigerant conduit 10. For instance, as shown in Figure 4, the fins 12 and conduit 14 may be soldered or brazed together so that there is a direct metallic path for 40 quick heat conduction. This is an important feature of the invention as will hereinafter become obvious.
- I provide a means for heating the defrosting fluid 24 either by heating the exterior of the tank 16, or as shown in Figure 3, utilizing a metal tube 26 inclosing a heating element 28 to heat the fluid by direct contact therewith, the tube 26 being immersed in the fluid. The heating element 28 is preferably of the electric type 50 and of course suitably insulated from the tube 26.
- Instead of having the tank 16, it is obvious that the ends 14a and 14b of the conduit 14 can be directly connected together and means associated with some part of the conduit to heat the fluid therein.
- I have the ends of the conduit 14 connected with the top and bottom of the tank 16 for the following purpose. Whenever the heating element 28 is energized, it will heat the fluid 24 in the immediate vicinity of the tube 26 and it is well known, of course, that where a portion of a body of fluid is heated, the heated fluid will tend to flow upwardly.
- 65 Therefore, soon after the heating element 28 is energized, a circulation of the fluid 24 through the conduit 14 will begin, the direction of circulation being indicated by the arrows 30 in Figure 1. The colder portion of the fluid 24 will then be drawn into the bottom of the tank 16. This is known as the thermo-syphon principle and by utilizing it, I do not need any mechanical means for circulating the fluid 24, although such means can be provided if found desirable, especially in 70 large installations.

The fluid 24 may be a brine solution because brine does not freeze until a much lower temperature than the freezing point of water is reached. In installations where colder conditions are encountered, however, there might be a tendency 5 for the fluid 24 if it is brine to become slushy and deter proper circulation. In such an installation, fluid with a lower freezing point should be used such as a calcium solution.

From the foregoing description, it will be obvious that I have provided a defrosting unit which when the heating element 28 is energized, will cause circulation of a hot fluid through a conduit which is in heat conducting relation to the cooling unit of a refrigerator. The result is 10 a diffusion of the heat from the fluid 24 to the fins 12 and to the refrigerant conduit 10 which is extremely rapid, resulting in melting of the frost on the cooling unit without appreciably raising the temperature of the space surrounding 20 the cooling unit during the defrosting operation. After the frost is all melted, of course, the temperature of such space could be quickly raised by continuing the operation of the defrosting unit, but if the current to the element 28 is shut 25 off just before complete defrosting has occurred the residual heat in the defrosting unit will finish the defrosting operation without raising the temperature of such space and thereby greatest efficiency is obtained.

It is desirable, of course, to control the operation of the defrosting unit automatically so that it needs no personal attention. This can be done by controlling the energization of the heating element 28 in accordance with the temperature of 35 one of the fins 12. As a matter of fact, the temperature of one of the fins in an operating refrigerator becomes lower in proportion to the thickness of the frost thereon because the thicker the frost, the more insulating effect it has on the 40 fin, thereby indirectly causing the refrigeration mechanism to operate longer each cycle of operation to produce the same temperature in the refrigerator in which the cooling unit is mounted. When the fin reaches an undesirable low or a pre-determined lower than normal temperature, its 45 temperature can be utilized to operate the control device C to thus automatically control the defrosting unit as will now be described.

The control C comprises a switch box 32 in 50 which is mounted an ordinary refrigerant compressor control switch mechanism C' and a special control switch mechanism C'' for controlling my defrosting unit.

I have shown the two switches combined in 55 one casing as this would be the convenient way to make them, but of course a separate control for the defroster alone could be used and it could be merely hooked into the line in series with the ordinary refrigerant compressor control switch 60 such as C' already existing on a refrigerant system.

The control switch C' is of the temperature responsive type having a bulb 34 mounted in the food compartment or other portion of the refrigerator so as to automatically maintain the refrigerator at a predetermined temperature. This switch as well as the switch C'' is shown more or less diagrammatic as the specific details do not form any part of my present invention.

Referring to the switch C' briefly, a bellows 36 is connected by a tube 38 with the bulb 34. Upon an increase of pressure, as caused by an increase of temperature in the refrigerator, a roller 40 passes center of a cam arm 42 to tip a mercury 70 75

5 tube switch 44 to the "on" position. Upon a decrease of temperature, as caused by operation of the refrigerant compressor, the motor of which is shown at 46, the bellows 36 will be contracted by an adjusting spring 48 for tipping the switch 44 to the "off" position. This is the ordinary automatic control for a refrigerant compressor motor to keep the temperature of a space in which the cooling unit is mounted between certain predetermined limits.

10 The switch C' comprises a bellows 50 connected by a tube 52 with a bulb 54. The bulb 54 is connected by a clip 56 directly to one of the fins 12 or may be brazed thereto or otherwise related by good temperature conducting connection with a portion of the cooling unit A. The bellows 50 acts upon an arm 58 in opposition to an adjustable spring 60. A roller 62 is held by a spring 64 against a cam arm 66 on which a double throw mercury tube switch 68 is mounted. Upon an increase of temperature, the roller 62 will pass center of the cam arm 66 and tip the switch 68 from the position shown in Figure 1 to an opposite position.

15 It will be noted that in the position shown, current is being conducted to the heating element 28 and by tracing the wiring, it will be obvious that when the switch is tipped to the opposite position, the heating element 28 will be de-20 energized and the switch C' will then be in the normal position for allowing the refrigerant compressor motor 46 to be again energized, depending upon the control switch C'.

25 From the foregoing it will be obvious that I have provided means for positively preventing any operation of the refrigerant compressor during the defrosting operation as such operation of the refrigerant compressor would merely be a waste of electricity because of refrigerating and defrosting at the same time.

30 After the defrosting operation, however, is completed, the refrigerating operation will be automatically continued in the normal manner.

35 If it is desired to have defrosting occur at a lower temperature, the adjustable spring 60 can be loosened. The length of the defrosting operation can be determined by adjusting the spring 64 which widens the differential of operation of the switch C' to thus provide a longer period of time between establishing and disconnecting the supply of current to the heating element 28.

40 The method I have provided for defrosting a cooling coil is very efficient because it only raises the temperature of the cooling fin sufficient to substantially completely defrost it and then is cut off so that residual heat after defrosting is not present. The entire operation is automatic and is accomplished in a minimum of time compared with other defrosting systems.

45 As far as the apparatus is concerned, it may be applied to different types of cooling units and by way of illustration I have shown a jacket type in Figure 5. In this type there are usually inner and outer walls 70 and 72 between which the refrigerant fluid flows. I have shown a defrosting fluid conduit 15 which may be of any desired shape but which should be in good heat conducting contact with the cooling unit.

50 For instance, it might be a round tube flattened as illustrated and brazed to the wall 72 before the cooling unit is enameled. Thus the enameeling will also cover the conduit 15.

55 In Figure 6 I have shown the plate coil type of cooling unit in which a refrigerant coil 11 extends through a metal casing 13, air circulation being

provided through the casing. In this type of unit, frost forms on the outside of the casing 13 and a defrosting fluid channel 15a may be brazed to the casing 13 so that the fluid 24 is in direct contact with the casing. Such direct contact or even the metallic contact illustrated in the prior figures provides for ready transmission of heat from the fluid 24 to the parts to be defrosted.

60 Although I have heretofore in my specification referred to fluid 24 in the conduit 14, I do not wish to be limited to fluid only. Any circulatable medium such as gas or steam could be used instead of fluid. It is well known that steam or gas can be readily circulated and therefore when in hot condition it can be circulated through the 15 conduit 14 for heating the conduit and defrosting the cooling unit.

65 My method can be somewhat modified, changes may be made in the arrangement and construction of the various parts of my apparatus for 20 practising the method and any suitable circulatable medium can be used without departing from the real spirit and purpose of my invention. It is, therefore, my intention to cover by my claims, any modified method or forms of the apparatus or 25 use of mechanical equivalents, which may be included within their scope.

70 I claim as my invention:

1. The method of defrosting a cooling unit comprising circulating fluid through a conduit 30 which is in heat conducting relation to the cooling unit, heating said fluid to cause such circulation upon an undesirable low temperature condition of said cooling unit being reached, the commencement of such heating and thereby the 35 control of such circulation being indirectly caused by the accumulation of frost on said cooling unit.

2. Apparatus for defrosting a cooling unit comprising a fluid conduit in heat conducting relation to said cooling unit, fluid in said conduit, means 40 for heating said fluid and means responsive to a predetermined low temperature condition of the cooling unit to control said means for heating the fluid.

3. Apparatus for defrosting a cooling unit comprising a fluid conduit in heat conducting relation to said cooling unit, fluid in said conduit, electric means for heating said fluid and means responsive to a predetermined low temperature of the cooling unit to control the energization of said 50 electric means.

4. Apparatus for defrosting a cooling unit comprising a fluid conduit in heat conducting relation to said cooling unit, fluid in said conduit, electric means for heating said fluid and a switch responsive to a predetermined low temperature of the cooling unit to control the energization of said 55 electric means.

5. Apparatus for defrosting a cooling unit which has mechanical means for reducing the 60 temperature thereof comprising a fluid conduit in heat conducting relation to said cooling unit, fluid in said conduit, means for heating said fluid and automatic means responsive to a predetermined low temperature condition of said cooling 65 unit to render said means for heating the fluid operative and said mechanical means inoperative.

6. Apparatus for defrosting a cooling unit which has electric refrigerating means for reducing the temperature thereof comprising a fluid 70 conduit in heat conducting relation to said cooling unit, fluid in said conduit, electric heater means for heating said fluid and an automatic switch responsive to a predetermined low temperature of the cooling unit to energize said electric 75

- heater means and de-energize said electric refrigerating means.
7. Apparatus for defrosting a cooling unit comprising a fluid conduit in heat conducting relation to the cooling unit, fluid in said fluid conduit, means for heating said fluid and settable means responsive to the temperature of said cooling unit to control said means for heating the fluid, said settable means being set for an undesirable low temperature of said cooling unit.
8. Apparatus for defrosting a finned cooling unit comprising a fluid conduit in heat conducting relation to the fins thereof, fluid in said conduit, means for heating said fluid and means responsive to the temperature of said fins to control said means for heating the fluid.
9. The method of defrosting a cooling unit comprising the circulation of heated fluid through a conduit which is in heat conducting relation to the cooling unit and the control of said circulation in direct accordance with the temperature of the cooling unit itself.
10. In a refrigerating system, the method of defrosting the cooling unit thereof which comprises subjecting the cooling unit to a source of heat extraneous of the system and controlling the application of such source of heat in response to an undesirable low temperature of the cooling unit.
11. In a refrigerating system in which frost forms on the cooling unit thereof due to the circulation thereover of the medium cooled thereby, the method of removing the frost from the cooling unit which comprises subjecting the cooling unit to a generated heat and controlling the application of said generated heat in response to an undesirable low temperature of the cooling unit.
12. In a refrigerating system, the method of refrigerating the cooling unit thereof and removing the frost formed on the cooling unit due to the circulation thereover of the medium cooled thereby, which method comprises circulating a cooling medium through the cooling unit, subjecting the cooling unit to a generated heat and discontinuing the circulation of such cooling medium and controlling the application of generated heat and the circulation of the cooling medium in accordance with the temperature of the cooling unit.
13. Refrigerating apparatus comprising in combination a cooling unit, means for cooling said unit and means for defrosting the cooling unit, said latter means including a source of generated heat and means responsive to an undesirable low temperature of the cooling unit for controlling the application of said generated heat to the cooling unit.
14. Refrigerating apparatus comprising in combination a cooling unit, means for circulating a refrigerating medium through said cooling unit, means for defrosting the cooling unit including an extraneous source of heat and temperature responsive means responsive to a predetermined low temperature of the cooling unit for controlling the application of said source of extraneous heat.
15. Refrigerating apparatus comprising in combination a cooling unit, means for circulating a refrigerating medium through said cooling unit, means for defrosting the cooling unit including an extraneous source of heat and temperature responsive means responsive to a predetermined low temperature of the cooling unit for controlling the application of said source of extraneous heat and being responsive to an increased temperature of the cooling unit for discontinuing the application of the source of extraneous heat.
16. Refrigerating apparatus comprising in combination a cooling unit, means for circulating a refrigerating medium through said cooling unit, means for defrosting the cooling unit including an extraneous source of heat and means responsive to an undesirable low temperature of the cooling unit for controlling the application of said extraneous source of heat and for rendering the circulating means ineffective.
17. Refrigerating apparatus comprising in combination a cooling unit, means for cooling said unit and means for defrosting the cooling unit, said latter means including a source of generated heat and means for controlling the application of said generated heat to the cooling unit, said last means including mechanism responsive to an increased temperature of the cooling unit caused by the application of said generated heat for discontinuing the application of said generated heat.
18. Refrigerating apparatus comprising in combination a cooling unit, means for cooling said unit and means for defrosting the cooling unit, said first means during cooling operation normally operating to cause frost to accumulate on the cooling unit due to the circulation thereover of the medium cooled thereby, said latter means including a source of generated heat and means for controlling the application of generated heat to the cooling unit, said last means including mechanism responsive to an increased temperature of the cooling unit caused by the application of said generated heat for discontinuing the application of generated heat and for restoring the system to normal condition.
19. Refrigerating apparatus comprising in combination a cooling unit, means for circulating a refrigerating medium through the cooling unit, said means normally operating to cause frost to accumulate on the cooling unit due to the circulation thereover of the medium cooled thereby, means for defrosting the cooling unit including an extraneous source of heat and means for controlling the application of said extraneous source of heat to the cooling unit, said last means including mechanism responsive to an increased temperature of the cooling unit caused by the application of said extraneous source of heat for discontinuing the application of said heat.
20. Refrigerating apparatus comprising in combination a cooling unit, means for circulating a refrigerating medium through the cooling unit, said means normally operating to cause frost to accumulate on the cooling unit due to the circulation thereover of the medium cooled thereby, means for defrosting the cooling unit including an extraneous source of heat and means for controlling the application of said extraneous source of heat to the cooling unit and for rendering the circulating means ineffective, said last means including mechanism responsive to an increased temperature of the cooling unit caused by the application of said extraneous source of heat for discontinuing the application of said heat and for rendering the circulating means effective.
21. The method of defrosting a cooling unit comprising heating a medium, circulating said medium when heated and which is in heat conducting relation to the cooling unit and controlling

- such circulation responsive to an undesirable low temperature of the cooling unit.
22. In a refrigerating system, the method of defrosting the cooling unit thereof which comprises externally subjecting the cooling unit to a temperature of greater than 32° F. and controlling the discontinuation of such temperature subjection in response to a predetermined rise in the temperature of the cooling unit caused by such temperature subjection. 5
23. In a refrigerating system including refrigerating mechanism, the method of defrosting the cooling unit thereof which comprises externally subjecting the cooling unit to a temperature of greater than 32° F. and controlling the discontinuation of such temperature subjection and the starting of said refrigerating mechanism in response to a predetermined rise in the temperature of the cooling unit caused by such temperature subjection. 10
24. The method of defrosting a cooling unit comprising circulating a normally dormant medium through a conduit which is in heat conducting relation to the cooling unit and controlling said circulation only in response to an undesirable low temperature of said cooling unit. 15
25. The method of defrosting a cooling unit comprising circulating heated fluid through a conduit which is in heat conducting relation to the cooling unit and controlling such circulation in accordance with an undesirable low temperature condition of said cooling unit as indirectly caused by the accumulation of frost thereon. 20
26. For use with a cooling unit, defrosting apparatus comprising a fluid conduit independent of and in heat conducting relation to said cooling unit, a part thereof being spaced from said unit, fluid in said conduit and electric heating element means for heating said part and thereby the fluid therein. 25
27. Apparatus for defrosting a cooling unit including a refrigerant conduit and fins thereof comprising a closed defroster conduit independent of said refrigerant conduit and in heat conducting relation to said fins, a circulatable medium in said defroster conduit and means for heating said medium. 30
28. Apparatus for defrosting a cooling unit comprising a closed fluid conduit in heat conducting relation to said cooling unit, fluid in said conduit, means for heating said fluid and automatic means responsive to undesirable low temperature of the cooling unit for controlling said heating means for heating said fluid only when said means responds to an undesirable low temperature. 35
29. Apparatus for defrosting a cooling unit including a refrigerant conduit and fins thereof comprising a fluid conduit distinct from said refrigerant conduit and in heat conducting relation to said fins thereof, fluid in said fluid conduit and means for heating said fluid and thereby causing thermo-syphon flow of the fluid through said fluid conduit. 40
30. Refrigerating apparatus comprising in combination a cooling unit, means for circulating a refrigerating medium through the cooling unit, means for applying heat to said cooling unit in response to a predetermined frosting of said unit resulting from the circulation thereover of the medium to be cooled and by such application of heat freeing the unit from said frost, and means arranged to render inoperative the heat applying means when the temperature of the cooling unit rises above a frost melting temperature. 45
31. In a refrigerating system, the method of defrosting the cooling unit thereof which comprises subjecting the cooling unit to a temperature of greater than 32° Fahrenheit by applying heat thereto, discontinuing refrigeration in said cooling unit, and causing a predetermined rise in temperature of the cooling unit caused by such heat application to discontinue the latter. 50

FRED B. FINK.
